CIRCUIT BREAKER

Kenneth R. Nisbet, Washington, D. C.

Application November 21, 1936, Serial No. 112,151

11 Claims. (Cl. 200—116)

This invention relates to a circuit breaker of moderate rating, suitable for use in the control of lighting circuits and comparatively small power applications and that is automatically operable to an open position upon overload, manually operable to either an opened or closed position, and has for an object a unit that is small and relatively inexpensive.

Another object of the invention is to provide a circuit breaker more compact than any heretofore available and one that can be utilized in connection with standard single type switch outlet boxes, standard ganged boxes, standard gang boxes with plaster covers or with special boxes if such is to be desired.

Another object of the invention is to provide a circuit breaker that is interchangeable with many types of tumbler switches already installed, and one that is operated as a tumbler switch in that there is no neutral position of the operating handle, with the attendant disadvantages thereof.

A still further object of the invention is to provide a circuit breaker having inverse time overload trip characteristics with the advantages of an ordinary tumbler switch thus combining some of the merits of both.

Other objects and advantages of the invention will be apparent in the description following hereinafter.

With reference to the accompanying drawings: Fig. 1 is a plan view, partly in section, of the circuit breaker installed within an ordinary sectional type flush mounted outlet box.

Fig. 2 is an elevation taken along line a—a of Fig. 1, showing the circuit breaker in the closed position.

Fig. 3 is a part elevation, showing certain elements of Fig. 2, with the circuit breaker in the normal opened position.

Fig. 4 is an isometric drawing of the carrier assembly drawn to a larger scale, in a position approximately midway between the opened and closed positions, drawn for the purpose of clarification.

Fig. 5 is a section thru Fig. 4, with the side plates and spring members added.

Figs. 6 and 7 are part sections thru the operating and contact carrier heads showing the relative positions of the pawl, in the circuit breaker opened and closed positions respectively.

Figs. 8 and 9 are part plan views of the operating and carrier heads respectively.

Fig. 10 is an isometric drawing of the trip and terminal assembly.

Fig. 11 is an alternate form of a bimetallic thermal element.

Fig. 12 is an alternate form of contact between the thermal element and the circuit breaker releasing device.

Figs. 13 and 14 are drawings in part showing a multi-pole circuit breaker having separable contacts.

By reference to Fig. 1, the numeral 1 represents a standard sectional conduit type outlet box, 10 commonly used for wall switches and receptacles, in which the circuit breaker is installed. The use of this particular type of outlet box is not restrictive inasmuch as the common switch boxes or fittings in general usage can be utilized equally 15 as well, which includes gang and gangable switch boxes or special boxes. The mechanism is contained within housing 2, having paper or fibre insulation 2a over the top, which is constructed of an insulating material and which has one 20 removable side 3 for assembly purposes. The housing is secured to the outlet box and covered in a manner similar to that used for ordinary tumbler switches, by means of yoke 4 and cover plate 5. The mechanism is in general supported 25 in a frame 6 consisting essentially of stop bar 7, pin 8, shafts 9, 10, 11, and two identically constructed side plates, only one 12 of which is shown on the drawings, the other side plate 13 being similarly located with respect to the horizontal axis and is so designated in Fig. 2.

It is to be noted that pin 8 extends into both sides of housing 2 thru side plates 12 and 13, to form a pivot for frame 6 which has a small angular movement, to be described hereinafter. 35 It should also be noted that stop pin 14 and trip pin 15 extend into both sides of housing 2 and are rigidly secured in place.

The carrier assembly shown in Figs. 4 and 5 consists of two units, one an operating carrier 40 16 having a radially curved head 17, a supporting leg 18, the end of which is formed to provide a means for an axis to coincide with that of head 17, the said end being provided with a guide 19 mechanically secured thereto, one edge of said end being cut away or otherwise formed to provide catch 20 which is utilized in connection with the tripping mechanism as covered hereinafter. Head 17 has operating handle 21 mechanically secured thereto and which is of an insulating 50 material, the mechanical attachment likewise furnishing the means of support for spring 22 which is biased to the curvature of head 17 to hold pawl 23 in a normally closed position. Pawl 23 is movable with shaft 24 which in turn is

supported by bearings 25 and 26 formed by projections from head 17. The other unit of the carrier assembly is contact carrier 27 which has a radially curved head 28 but of a smaller radius than that of head 17, and formed in a manner such that one operates within the other, a supporting leg 29, which is drilled to support the electrical contacts as described hereinafter, and has its end similarly formed but in the opposite manner to catch 20, to provide catch 30, and has guide 31 mounted thereon. Fig. 5 is a cross-section of Fig. 4, at right angles thereto, and shows the relative positions of plates 12 and 13 to operating carrier 16 and contact carrier 27. Spring elements 32 and 33 are mounted about their respective guides 19 and 31, their outer ends being secured to plates 12 and 13, their inner ends being in contact under tension to legs 18 and 29 thereby biasing both operating carrier 16 and contact carrier 27 to their normal positions in which the circuit breaker is open. Washer 34 is merely a separating means and an assistant for maintaining alignment of its adjacent parts. Shaft 9 is the common support for carriers 16 and 27.

Part plan views of the pawl ends of heads 17 and 28 are shown in Figs. 8 and 9 respectively. Head 17 is projected on both sides, which projections are formed to provide bearings 25 and 26 while the top inner edge 35 is flat beveled to form a bearing surface for the extreme tip of pawl 23. Head 28 has a longitudinal slot 36 near the end with a rounded or beveled portion 37 between the slot and the end.

To open the circuit breaker manually, the following operation is described, with particular reference to Figs. 2, 4 and 5:—A counterclockwise force is applied to handle 21 which force is transmitted thru leg 18 to shaft 9 thence to frame 6 thru side plates 12 and 13. The aforesaid force acting thru the described linkage causes frame 6, with all its subjoined parts, to rotate counterclockwise thru a small angle about pin 8 against the bias of spring 38. In this angular movement, projection 39 of latch-lever 40 is brought into contact with trip pin 15, which being stationary within housing 2, causes the aforesaid latch-lever 40 to rotate about its shaft 10 which movement in turn causes tip 41 to be tripped from catches 20 and 30 thus releasing both the operating carrier 16 and contact carrier 27 which being under bias from springs 32 and 33 quickly rotate to their normally open position as shown in Fig. 3. Mercury contact element 42 being secured to leg 29 is tilted to an off position whereby the mercury 43 within the container flows by gravity away from electrodes 44 and 45, thus breaking the electrical circuit. In the first part of this operation as operating carrier 16 and contact carrier 27 are tripped, frame 6 is returned to its normal position with side plates 12 and 13 in contact with stop pin 14, by virtue of the tension in spring 38.

Fig. 10 shows the relative positions of the trip and terminal assembly, consisting essentially of thermal element 46, latch-lever 40 on its shaft 10, spring member 48, trip pin 15, terminals 46b, 46c and 46d. The action is described as follows: Current from the external source enters the assembly thru wire terminal 46c, flows thru both legs of thermal element 46 to terminal 46d thence by flexible connectors, which are not shown, to the mercury contact element, thence back to wire terminal 46b to complete the circuit. If the current is ex-

cessive, the free end 46a is deflected which movement is transmitted thru insulator 47 to rotate latch-lever 40 on or about its shaft 10, to trip the circuit breaker as described elsewhere herein. Spring member 49 normally holds latch-lever 40 approximately parallel to thermal element 46.

Automatic operation of the circuit breaker due to excessive current takes place in the following manner, reference being made to Figs. 2, 3 and 4: Current in excess of a predetermined figure thru bimetallic element 46 causes the free end 46a to deflect in the usual manner. This movement is transmitted thru insulating pin 47 to projection 48 of latch-lever 40 thereby rotating the same on or about its shaft 10 against the bias of spring element 49 moving tip 41 from faces 20 and 30 thereby releasing operating carrier 16 and contact carrier 27 to their open positions as noted hereinbefore. Mercury contact element 42 being secured to leg 29 of contact carrier 27 breaks the electrical circuit in the manner noted above. The circuit being thus interrupted, current ceases to flow and thermal element 46 gradually resumes its normal position due to the cooling effect. In the tripped position of the circuit breaker, projection 39 of latch-lever 40 is in contact with the radially curved ends of legs 18 and 29 and is under bias from spring element 49. It is to be noted that with the circuit breaker in the tripped position, projection 50 of latch-lever 40 is in a position to strike projection 51 of pawl 23 upon reclosure of the circuit breaker unless the free end 46a of thermal element 46 is in its normal position, thus preventing immediate reclosure following a severe overload.

Fig. 6 shows the relative positions of pawl 23, heads 17 and 28 when the circuit breaker is open. Upon the approach to the open position, contact carrier 27 is first stopped followed by operating carrier 16 as their respective heads 28 and 17 strike stop bar 7, as noted in Fig. 3. Pawl 23 moves with head 17 by virtue of its mounting, and projection 52 being biased by spring 22 impinges and rides over rounded surface 37 falls into slot 36 and thereby engages head 28 which in turn causes carrier 16 to be latched to carrier 27 for the closing operation.

To close the circuit breaker, a clockwise force is applied to operating handle 21 to move carrier 16, hence carrier 27, hence mercury contact element 42 in the same direction about shaft 9. With thermal element 46 in its normal position, the above described rotation is continued until portion 53 of pawl 23 strikes stop pin 14 which action rotates pawl 23 to release head 28, hence carrier 27, permitting the motion of said carrier 27 to be reversed, which reverse motion is arrested as tip 41 engages face 30. Upon the release of handle 21, carrier 16 moves counterclockwise thru a small angle until face 20 is similarly engaged by tip 41. Mercury contact element 42 now being in a horizontal position, mercury 43 surrounds both electrodes 44 and 45 to close the electrical circuit. If thermal element 46 is in an abnormal position, projection 50 interferes with the clockwise motion of pawl 23, trips the same as projection 51 strikes projection 50 which prematurely releases head 28 hence carrier 27 hence mercury contact element 42 to prevent reclosure of the circuit breaker electrical contacts.

Fig. 7 shows the relative positions of pawl 23, heads 17 and 28 when the circuit breaker is

closed. It is to be noted that the said heads 17 and 28 are disengaged as projection 52 rests upon surface 37 beyond slot 36.

It is to be noted that by the use of mercury contact element 42, the circuit breaker is successfully operable only when installed in a vertical position. To avoid this requirement, I propose to utilize separable contacts in lieu of the said mercury contact element, for single or multi-pole service, as is indicated in Fig. 13. The use of such separable contacts will permit increased current ratings thus permitting a wider range of the circuit breaker utilization.

The design, type and location of spring member 38 is that of a preferred example but it is not to be so restricted as to exclude the use of another member of different design, type or location to serve the same purpose, that of maintaining frame 6 in its normal position within housing 2. The U-shaped bimetallic thermal element 46 noted in Fig. 10 is not necessarily that of a preferred example inasmuch as an elongated element of the bar type, or one of the type indicated in Fig. 11 may be utilized, with modifications in the wire terminal arrangement on housing 2.

It is not intended that the curvature of tip 41 or the angularity and respective lengths of catch faces 20 and 30 be restricted to the design shown on the drawings inasmuch as with modifications thereof and with consideration given the lengths of the lever arms and spring members involved, the sensitivity of the tripping arrangement can be reasonably governed, an important factor when dealing with comparatively low current values.

Fig. 11 shows an alternate form of a bimetallic thermal element consisting of an elongated portion of thermostatic metal or of dissimilar metals generally utilized for such purposes, having a terminal means 54 at each end. A raised portion 55 is provided along the center line of the element, in order to add rigidity to the unit, which may be formed in either of the metals or both.

Latch-lever element 40 is constructed preferably of an insulating material but is not to be so restricted inasmuch as it may be of metal of a slightly different form.

Insulating pin 47 may be eliminated by incorporating its function in another projection 47a to latch-lever 40 as is indicated in Fig. 12, which serves to eliminate any intermediate element between latch-lever 40 and thermal element 46.

Figs. 13 and 14 show a part assembly of a multi-pole circuit breaker in which the various elements covered hereinbefore are incorporated but with modifications that are covered in the following description. The assembly as indicated is based upon the same fundamental operating principles for manual and automatic operation, having a movable frame, operating carrier and contact carrier elements, trip assembly, latching elements, pins, stops, shafts and housing similar in functions to these previously described but modified for a multi-pole arrangement with separable contacts and to be utilized in connection with standard gang outlet boxes or ganged single boxes or with special boxes.

The basic elements noted consist of an insulating housing 56, side plate 57, operating carrier leg 58, contact carrier leg 59, biasing means guides 60 and 61, stop bar 62, frame pivot pin 63, and latch-lever 76, other parts and numerals being omitted in order to simplify the drawings.

To leg 59 is mechanically secured an insulating block 64 which serves as a support for one

end of spring member 65 on the other end of which is secured insulator 66 which has mounted thereon contacts 67, 68, 69 arranged to provide wire terminals for the fixed ends of thermal element terminals 70, 71 and 72, the latter not 5 being visible in the drawings, by means of flexible conductors 73, there being one such per thermal element. Insulating barriers 74 are provided between adjacent pole terminals and one bar type thermal element 75 is provided per pole. Latch-lever 10 10 has secured thereto, or an integral part thereof, plate 77 which extends across the free ends of all thermal elements 75 in order to receive the motion of either one or all said thermal elements upon an electrical overload. Stationary contacts 76, 77 and 78 extend thru housing 56 to provide one set of wire terminals 79. Flexible conductors 80 connect the free ends of thermal elements 74 to the other set of wire terminals 81. 20

Operation of the circuit breaker, either manually or automatically, so far as linkages of mechanical parts are concerned, is as described hereinbefore. Automatic operation from a closed to an open position is described in part as follows: Current in excess of its rating will, in one or more thermal elements 75 either individually or collectively, cause the same to deflect against plate 77 thus rotating latch-lever 76 on or about shaft 82 which trips legs 58 and 59 to their 30 normally biased positions, thereby quickly rotating block 64, spring member 65, insulator 66 with contacts 67, 68, 69 all in a counterclockwise direction thus breaking the electrical contact with stationary contacts 76, 77, 78 to interrupt 35 the electrical circuit.

Spring member 65 is so utilized with the forms of contacts noted to permit some latitude due to the movement of the frame in the manual opening operation. With knife contacts in lieu 40 of buttons, block 64, member 65 and insulator 66 may be of unit construction or member 65 may be rigid.

It is to be understood that the forms of this invention herewith shown and described are to 45 be taken as preferred examples of the same, and that various changes in the shape, size and arrangement of parts may be resorted to without departing from the spirit of the invention or the scope of the subjoined claims.

Having thus described the invention, I claim:

1. In a device of the class described in combination, a means responsive to a predetermined circuit condition for interrupting a circuit and manually operable to either close or interrupt 55 said circuit, consisting of an insulating housing; a movable supporting member; an operating element; a switch element; a releasable latch element for connecting said operating element to said switch element thru the closing cycle; a 60 means fixed to said housing for tripping said latch element; a separate biasing means for each item listed above, that is to say, the supporting member, the operating element, the switch element, and the latch element; a releasable latch-lever element for locking said operating element and said switch element in a closed 65 position; a biasing means for said latch-lever element; the said latch-lever element being pivoted and releasable by a fixed means to rotate 70 the said element about its axis in the manual opening operation and by a thermal element in the automatic operation, the said latch-lever element having two projections, one on either side of its said axis to provide for the said rotation 75

and still another projection arranged to intercept said releasable latch element to prevent reclosure unless the said thermal element is in approximately its normal position; the said switch element having a means for mounting one or more contacts thereon.

2. In a device of the class described in combination, a means responsive to a predetermined circuit condition for interrupting a circuit and 10 manually operable to either close or interrupt said circuit, consisting of an insulating housing; a movable supporting frame; an operating element; a switch element; a releasable latch element for connecting the said operating element to the said switch element thru the closing cycle; a fixed means for tripping said latch element, the said means being fixed to said housing; a biasing means for each of—the 15 said frame, the said operating element, the said switch element, the said latch element; a releasable latch-lever element for locking said operating element and said switch element in a closed position; a biasing means for said latch-lever element; the said latch-lever element being 20 pivoted and releasable by a means fixed to said housing to rotate said element about its axis in the manual opening operation and by a thermal element in the automatic operation, said latch-lever element having two projections, one 25 on either side of said axis to provide means for said rotation and still another projection arranged to intercept said latch element unless said thermal element is in its approximately normal position; said switch element having a plurality 30 of contacts mounted thereon.

3. In a device of the class described in combination, an operating means; a switch element; a biased releasable latch for connecting said switch element to said operating means thru the closing cycle; a tripping means embodying a bimetallic thermal element; a biased releasable latch element for holding said switch element in a predetermined position and for tripping said switch element under a predetermined 40 circuit condition, said latch element being pivoted and movable about an axis centrally located and having one projection moving generally in the same direction with the free end of said thermal element, another projection moving in the 45 opposite direction and still another projection moving generally at a right angle to that of the free end of said thermal element, one said projection operating in connection with said switch element, another said projection operating 50 in connection with said thermal element and the other said projection operating in connection with said releasable latch; an insulating housing provided with terminals.

4. In a device of the class described in combination, a main supporting element within an insulating enclosure; an operating means embodying a biased pivoted member having an insulating operating handle affixed thereto; a switch member having a mercury contact element attached thereto; a biased pivoted releasable means for latching said operating means to said switch means, said releasable means having a projection thereon for said latching purpose, another projection arranged to impinge against a fixed element 60 within said enclosure thereby rotating said releasable means at or near the closed position and thus releasing said switch member from said operating means, said switch member and said operating member thereby moving to their fully 65 opened positions ready for reclosure; a tripping 70 75

means embodying a biased releasable latch for retaining both said operating means and said switch member in the closed position; a bimetallic thermal element for operating said tripping means.

5. In a device of the class described in combination, a biased carrier assembly embodying an operating means and a switch element having attached thereto a contact assembly; a tripping assembly embodying essentially a releasable latch 10 and a bimetallic thermal element, the said thermal element being arranged to transmit a movement therefrom due to excessive current, directly to said releasable latch, said latch being biased and serving a purpose of retaining said 15 carrier assembly in a closed position, one projection of said latch moving generally in the same direction as the free end of said thermal element, one projection moving in the opposite 20 direction and another projection moving approximately at right angles to the direction of movement of said thermal element end.

6. In a device of the class described in combination, a main supporting element within an insulating enclosure; an operating means embodying a biased pivoted member having an insulating operating handle affixed to the head thereof; a switch member having a contact assembly attached thereto and movable about an axis common with that of the said pivoted member; a biased releasable means for latching said operating means to said switch member, supported by a pivoted means from said head of the aforesaid pivoted member; the said releasable means having a projection therefrom for the 25 said latching purpose and another projection arranged to impinge against a fixed element within the said insulating enclosure in order to rotate said releasable means about its pivot to release said switch member from said operating 30 means essentially at the closed position; a tripping means embodying a biased releasable latch-lever element for retaining both the said operating means and said switch member in the closed position by the engagement of one projection on said latch-lever element against catch 35 faces on the pivoted ends of said pivoted member and said switch member; a bimetallic thermal element for automatically operating said tripping means.

7. In a device of the class described in combination, a main supporting element within an insulating enclosure; an operating means; a switch element having a biased member pivoted about an axis coinciding with that of the said operating means and having secured thereto a contact assembly; the said switch element operating in planes parallel to and opposite said operating means and operatively connected to said operating means thru the closing cycle only by 40 means of a releasable latch element; a tripping assembly embodying essentially a bimetallic thermal element, a releasable latch-lever element for locking said operating means and said switch element in the closed position, said latch-lever element having a projection to provide the 45 said locking arrangement, another projection to contact said thermal element for automatic tripping and still another projection to trip the aforesaid releasable latch element in order to 50 release said switch element from said operating means prior to the normal closed position of the said switch element to prevent reclosure against overload; said thermal element being of the bar type having terminals at each end thereof. 55 60 65 70 75 80 85 90 95 98

8. In a device of the class described in combination, a main supporting element within an insulating enclosure; an operating means; a switch element consisting of a biased member pivoted about an axis coinciding with that of the said operating means and having secured thereto a contact assembly; the said switch element operating in planes parallel to and opposite said operating means and operatively connected to said operating means thru the closing cycle by means of a releasable latch element; a tripping assembly embodying essentially a bimetallic thermal element, a releasable latch element for locking said operating means and said switch element in the closed position, said releasable latch means having a projection therefrom to provide the said locking arrangement, another projection to contact said thermal element and still another projection to trip said releasable latch element to release said switch element from said operating means prior to the normal closed position of the said switch element.
9. In a device of the class described in combination, an insulating enclosure; a biased pivoted frame element; a biased switch element for opening and closing the circuit; a means for operating said switch element, said means being operatively connected to said frame element; a tripping assembly embodying a bimetallic thermal element; a biased controlling element operated by said thermal element, the said controlling element latching said switch element in the closed position and provided with a means to prevent said switch element being closed immediately following a severe overload, and being of unit construction having a circular movement about an axis and operatively connected to said frame element; said thermal element being of the bar type having a terminal means at each end thereof.
10. In a device of the class described, in combination, an insulating housing; a frame consisting of two plates similar in design and purpose, held apart by a plurality of separating means to form a nesting for a carrier assembly, the said frame being pivoted and biased to a predetermined position, said position being determined by an element fixed to said housing, against which element a projection on each said plate is in normal contact by virtue of the said biasing means; said carrier assembly embodying an operating member and a switch member having a contact assembly mounted thereon; a tripping means embodying a bimetallic thermal element and a latch-lever element, said latch-lever element being supported by the said frame and movable with said frame in its angular movement; a biasing means for said latch-lever element; said latch-lever element serving the purpose of locking said operating element and said switch element in a closed position and an additional purpose of preventing the final closing operation of the said switch element unless the said thermal element is in its near normal position; a means for tripping said latch-lever element independent of said frame; the said insulating housing being provided with wire terminal means.
11. In a device of the class described, a circuit breaker having a slow-make quick-break mechanism, embodying an operating element; a carrier element for electrical contacts, operatively connected with the said operating element during the closing cycle and latched thereto in the open position; said operating element and said carrier element each being biased and both supported by a common shaft fixed within a pivoted frame; a tripping assembly embodying in part a bimetallic thermal element; an insulating housing provided with wire terminals; said mechanism providing a means to quickly open said electrical contacts upon a predetermined circuit condition and to permit a manual reclosure with a slow motion in said carrier element.

KENNETH R. NISBET.
